TELEVISION RECEIVING ANTENNA FOR INDOORS

Margaret Kumpis and John B. Kumpis,
San Francisco, Calif.

Application October 7, 1954, Serial No. 32,573

Term of patent 7 years

(Cl. D26—14)

To all whom it may concern:

Be it known that we, Margaret Kumpis and John B. Kumpis, both citizens of the United States, residing in the city and county of San Francisco, State of California, have invented a new, original, and ornamental Design for a Television Receiving Antenna for Indoors, of which the following is a specification, reference being had to the accompanying drawing, forming part hereof, in which:

Figure 1 is a front elevation view of a television receiving antenna for indoors;

Figure 2 is a side elevational view thereof; and

Figure 3 is a top plan view of Figure 2.

We claim:

The ornamental design for a television receiving antenna for indoors, substantially as shown.
